UNITED STATES PATENT OFFICE.

JOHN W. WEST, OF EAST BRAINTREE, MASSACHUSETTS.

PROTECTOR FOR TUBE-THREAD.

1,038,249.

Specification of Letters Patent. Patented Sept. 10, 1912.

Application filed February 12, 1912. Serial No. 677,115.

To all whom it may concern:

Be it known that I, JOHN W. WEST, of East Braintree, in the county of Norfolk and State of Massachusetts, have invented 5 certain new and useful Improvements in Protectors for Tube-Thread, of which the following is a specification.

This invention relates to devices for protecting cops of thread during transport and 10 for use during unwinding, and is an improvement upon the protector for tube thread shown in my Patent No. 1,001,718, dated August 29, 1911. In said patent I have shown a protector for tube thread having 15 heads provided with hollow bosses or stems for engaging the interior of the tube upon which the mass of thread is wound. The device shown in said patent was adapted more particularly for use with tubes of 20 thread in which the end of the tube is substantially flush with the end of the mass of thread. There are many instances however in which the paper tube extends beyond 25 each end of the mass of thread a considerable distance.

I preferably provide suitable material between the ends of the mass of thread and the heads to prevent friction between the heads and the thread when the heads are forced 30 tightly against the thread. I have found a yielding material, such as felt, to be suitable for this purpose, although other material may be utilized. When the heads are forced tightly against the ends of the mass 35 of thread and given a relative rotary movement to produce intimate contact there is danger of injuring the thread. However, with some grades of thread I am able to dispense with this intermediate material.

Accordingly, a feature of the present invention contemplates the provision of one or more heads, each provided with a boss adapted to engage the exterior of the paper tube to firmly hold the head in place against 45 the end of the mass of thread, said head or heads being also preferably provided with peripheral flanges which aid in deflecting the thread as it is drawn off the mass, a protecting and packing material being preferably inscribed between each head and the opposing end of the mass of thread to prevent injury to the thread.

A further feature of the invention contemplates the provision of a thread guiding

arm which is adapted to be supported by 55 one of the protector heads. This arm is provided with a thread receiving or guiding eye, and is adapted to be detached from the head when the protector is shipped, but can be readily inserted in place when the 60 thread is to be used on a machine. By this arrangement, the upper head of the protector may remain removed, as shown in Fig. 5, while the lower head is used to support the thread. The lower head may also be utilized to support a spool instead of being connected to a tube, so that the head and thread guiding arm may constitute a thread stand, adapted for use either with tubes or with spools of thread. With this 70 construction the thread can be shipped in the protector and the thread guide sent with it detached therefrom but ready for insertion in the head, thus obviating the necessity of providing a separate stand for 75 holding the protector and guiding the thread during use.

It has been found that when thread is allowed to remain in contact with metal carriers, such as spools or the like, climatic 80 changes cause the metal to "sweat," or in other words the moisture in the atmosphere condenses on the metal. This moisture acting on the dye and other chemicals contained in the thread has a deleterious effect 85 on the thread, causing the latter to fade and deteriorate in strength. By preventing contact between the thread and the metal heads of my protector, I obviate the difficulties and objections incident to the use of 90 metal spools. Accordingly, I preferably leave an air space at the end of the mass of thread to prevent the metal head from coming in contact with the thread. I accomplish this result by making the inclosing 95 cylinder of such a length that the heads cannot be forced into contact with the ends of the mass of thread while the cylinder is in place about the thread.

I will describe my invention in the following specification and point out the novel features thereof in the appended claims.

In the accompanying drawing, Figure 1 is a sectional side elevation showing one embodiment of the invention as applied to a 105 tube of thread, Fig. 2 is a fragmentary vertical section of a modified form of the invention, Fig. 3 is a similar view of another

modified form, Fig. 4 is a view in elevation, on a reduced scale, of a tube of thread to which the protector is to be applied, and Fig. 5 is a side elevation of the protector with the thread guiding arm in position.

As illustrated in the drawing, 1 represents a tube, made of paper or other suitable material, upon which the mass of thread 2 is wound. This mass of thread is generally cylindrical and of any length and diameter, according to the number of yards and size of thread. In some forms of tube thread the tubes 1 extend a half inch, more or less, beyond the ends of the mass of thread 2. To affix the protector heads in the manner shown in my said patent would not be feasible with such tubes, since it would necessitate an excessive amount of felt, or other material, for packing between each head and the opposing end of the mass of thread.

I have found that by providing the protector heads with hollow bosses which engage the exterior of the tube 1, a comparatively thin sheet of packing suffices.

As shown in Fig. 1 the protector comprises a pair of heads 3, 4, preferably formed of sheet metal, and each provided with a thread deflecting flange 6. The head is preferably substantially flat and provided with a hollow boss 8. This boss, in the present instance, is smooth bored and adapted to tightly fit the exterior of the tube 2. This boss may be made of sheet metal and soldered to the head, or it may be made integral with the head and formed by spinning or otherwise. An annular ring or mass of packing material 10 is arranged to surround the tube 1 and loosely fit the same. The packing material is preferably made of felt or other similar material, although any other suitable material may be employed, and is put between the head and the end of the mass of thread and held in this position by the head to protect the end of the mass of thread from becoming jammed and the thread bruised by friction against the head. In the form illustrated in Fig. 2 the head 12 is provided with a boss 14 having spiral projections or screw threads 15, which are adapted to be embedded in the exterior of the tube 1. The boss 14 may be soldered to the head or it may be formed integrally therewith, as by spinning or otherwise.

In the form illustrated in Fig. 3 the head 16 is provided with a boss 18 having internal projections 20, which are adapted to be embedded in the exterior of the tube 1. The boss 18 may be soldered to the head, or it may be formed integrally therewith, as by spinning or otherwise, and the projections or small internal protuberances may be formed by upsetting the metal, as with a prick punch or similar implement.

In using the protector for a shipping case, the mass of thread is inclosed within a protecting covering, which may be in the form of a shell or cylinder 24 of card board, metal, or other suitable material. In some instances a paper wrapping may be placed about the mass of thread and extend between the heads. The shell 24 is preferably made of such a length that when the heads are forced up tightly against its ends, there will be an air space 25 between the ends of the mass of thread 2 and the material 10. The ends of the shell may abut against the packing 10, as shown, or they may engage the heads directly. This construction insures the protection of the thread from contact with the metal, and consequently prevents any chemical changes or other injurious effects which might result from such contact.

When it is desired to use the thread, the protecting shell may be torn or cut off, or one of the heads is removed from the tube and then the protecting shell or wrapping is removed. The head is then replaced upon the tube, or under some circumstances the upper head need not be replaced. The head or heads are then forced up tightly against the mass of thread to bring the packing material into intimate contact therewith, and then the thread is placed in position upon a suitable spindle. When the thread is being drawn off and reaches an end of the mass, the thread is guided away by the peripheral flange on the corresponding head and is prevented from breaking away the corners of the mass, and the packing material aids in preventing the thread from creeping between the protector heads and the mass of thread, thereby keeping the thread from snarling about the spindle.

To utilize the protector as a stand, an arm 26 may be provided, which is detachably connected at its lower end to a protector head, said head being preferably provided with a boss 28 on its periphery adjacent the thread deflecting flange 6. The upper end of the arm 26 is provided with a thread guide 30, through which the thread passes when drawn off for use. The arm 26 is preferably made of wire bent into the desired shape to suit the requirements. The arm 26 is detachable from the head of the protector, so that a number of protectors may be packed closely for shipment, and the arms packed separately, thus economizing space. It should be understood, however, that the protector may be used without the arm 26, if desired.

While I have illustrated and described a preferred embodiment of the invention, I am aware that many modifications can be made therein by any person skilled in the art without departing from the scope of the invention as expressed in the claims. There-

fore, I do not wish to be limited to all of the details of construction shown and described, but

What I claim is:

- 5 1. The combination with a tube having a mass of thread wound thereon, said tube having its ends projecting beyond the ends of the mass of thread, and a head having a boss arranged to engage the exterior of the tube to hold the head in place, substantially as described.
- 10 2. The combination with a tube having a mass of thread wound thereon, said tube having its ends projecting beyond the ends of the mass of thread, protecting material arranged at the end of the mass of thread, and a head adapted to be forced tightly against said protecting material when in use on a machine, said head being provided with a boss arranged to engage the exterior of the tube to hold the head in place against said material, substantially as described.
- 15 3. The combination with a tube having a mass of thread wound thereon, said tube having its ends projecting beyond the ends of the mass of thread, packing material arranged to cover the end of the mass of thread, and means to hold said packing material in intimate contact with the surface of said mass during use on a machine comprising a head having a hollow boss adapted to engage the exterior of the tube, substantially as described.
- 20 4. The combination with a tube having a mass of thread wound thereon, said tube having its ends projecting beyond the ends of the mass of thread, packing material adapted to cover the ends of the mass of thread, and a pair of heads arranged to engage said material to hold it in intimate contact with the ends of said mass during use on a machine, each head being provided with a boss adapted to engage the exterior of the tube to hold the head in place, substantially as described.
- 25 5. The combination with a tube having a mass of thread wound thereon, said tube having its ends projecting beyond the ends of the mass of thread, a pair of heads each having a boss arranged to engage the exterior of the tube to hold the head in place, and a protecting covering extending between said heads and surrounding said mass of thread, substantially as described.
- 30 6. The combination with a tube having a mass of thread wound thereon, said tube having its ends projecting beyond the ends of the mass of thread, and a head having a boss provided with projections arranged to be embedded in the exterior of the tube to hold the head in place, substantially as described.
- 35 7. The combination with a tube having a mass of thread wound thereon, said tube having its ends projecting beyond the ends of the mass of thread, and a head having a boss arranged to engage the exterior of the tube to hold the head in place, said head being provided with a peripheral flange, substantially as described.
- 40 8. A protector for tube thread, comprising a head having means for engaging the tube upon which the mass of thread is wound to hold the head in place against the thread, and a boss for holding a thread guiding arm at the periphery of said head, substantially as described.
- 45 9. A protector for tube thread, comprising a head having means for engaging the tube upon which the mass of thread is wound to hold the head in place against the thread, said head having provision for receiving a thread guiding arm, substantially as described.
- 50 10. The combination with a tube having a mass of thread wound thereon, of a shell surrounding said mass, and a pair of heads provided with packing material and arranged to hold said shell in place, said heads having means for engaging said tube to hold said heads in place thereon, said shell being of such a length that when the heads are in their innermost position the packing material is held out of engagement with the ends of the mass of thread, substantially as described.
- 55 11. The combination with a tube having a mass of thread wound thereon, of a shell surrounding said mass, and a pair of heads provided with packing material and arranged to hold said shell in place, said heads being provided with bosses arranged to engage said tube, said shell being of such a length that when the heads are in their innermost position the packing material is held out of engagement with the ends of the mass of thread, substantially as described.

In testimony whereof I have affixed my signature, in presence of two witnesses.
